Ms. 560

Letters Patent No. 560. Dated May 3^d 1853.

The schedule referred to in these Letters Patent and making part of the same

To all whom it may concern:

Be it known that I, James L. Jackson, of the city, County, and State of New York, have invented or produced a certain new and original design for a Grate-frame, and I do hereby declare the following to be a full, clear and exact description of the same reference being had to the accompanying drawing representing one half of the frame complete, the other half which is the same in configuration being shown in outline only, and representing by a sectional line the projection of the mouldings &c.

The jambs of the frame are straight and connected by a semi-circular top. The inner margin of the frame has a gothic bead, a, around it, from which extends a deep cavetto moulding b, until it meets the more bold projecting parts of the frame. On the base c, of the jamb is foliated scroll work d, partially covered by a fruit piece, e, which is suspended by a stem f, from a volute g, above it. From the top of this volute a stalk h, starts, and passes entirely around the frame, forming the inner margin of the projecting portion of the frame, which overhangs the cavetto moulding b. - The stalk h, is connected to the frame at intervals - first by a foliated scroll work piece i, having a shell centre piece j, and secondly by the top centre piece k, which is formed of a lozenge centre surrounded with deeply indented leaves. The space between the stalk and frame where not united by ornament is in open work, and from this part to the outer margin of the frame there is a series of bead, cavetto, and gothic mouldings, which complete the design.

The shaded line x, x, represents a cross section through the frame at the point where it is placed, which shows the projections of the various parts thereof.

Having thus fully described the nature of my design, What I claim therein as new and desire to secure by letters patent is the combination and arrangement of the figures, flowers and ornaments herein represented, the whole forming an ornamental design for a grate frame.
